UNITED STATES PATENT OFFICE.

PETER A. GOOD, OF PHILADELPHIA, PENNSYLVANIA.

MILK-BOTTLE HOLDER.

1,105,269.

Specification of Letters Patent. Patented July 28, 1914.

Application filed January 28, 1913. Serial No. 744,891.

To all whom it may concern:

Be it known that I, PETER A. GOOD, a citizen of the United States, residing in Philadelphia, Pennsylvania, have invented certain Improvements in Milk-Bottle Holders, of which the following is a specification.

My invention consists of a receptacle intended to be placed upon a door step for the reception of one or more milk bottles, one object of my invention being to provide simple and efficient means whereby the bottle, when inserted into the holder, serves to lock the parts of the latter in place and prevent the removal of the bottle from the top of said holder, and a further object is to provide effective means for locking the holder in place upon the door step in such manner that it cannot be manipulated so as to permit of the removal of the bottle from the bottom of the holder.

In the accompanying drawing Figure 1 is a sectional view of part of a door, door sill and door step with milk bottle holder secured in place upon the latter, the parts being shown in the position occupied by them when the bottle is being inserted into the holder; Fig. 2 is a similar view showing the relation of the parts to one another after the bottle has been thus inserted; Fig. 3 is a view of the lower portion of the holder illustrating the manner in which the bottle is removed therefrom after the holder has been taken from the door step, and Fig. 4 is a perspective view of a locking plate whereby the holder is, when the door is closed, retained in a certain position in respect to the door and door step.

In the drawing, 1 represents part of a door step, 2 the door sill, and 3 part of the door. The bottle holder comprises a back 4, opposite sides 5, a front 6, a top 8 and a bottom 9. The front 6 is pivoted, at 7, to the opposite sides 5 and the top 8 is secured to or formed in one piece with the front 6. The bottom 9 is pivoted at 10 to the opposite sides 5 and has a flange 11 overlapping the back 4, as shown in Figs. 1 and 2.

The front 6 and top 8 are stiffened at the edges by means of flanges 6^a and 8^a which meet at the angle between the top and front, as shown in Figs. 1 and 2, and are disposed on the inner sides of the side plates 5 of the body. Secured to and projecting inwardly from the front plate 6 below the pivot 7 is a cam 12 consisting, in the present instance, of a piece of bent wire, and secured to and

projecting outwardly from the front 4 of the holder, near each side of the same, is a lug 13 to which is connected one end of a chain 14 whose other end is connected to one of the outer corners of a curved plate 15 which bridges the door sill 2 and has at its inner end an upstanding flange 16.

The bottom of the holder is normally retained in position by means of a hook 17 pivoted to a projecting eye 18 on the flange 11 of said bottom and engaging with a staple 19 projecting from the front of the holder, as shown in Figs. 1 and 2.

The empty holder is placed upon the door step when the door 3 is open and the locking plate 15 is adjusted so as to bridge the door sill, as shown in Figs. 1 and 2, the inner end of said plate being then so far below the top of the sill that the projecting flange 16 will not interfere with the closing of the door over the plate, as shown in Figs. 1 and 2. If any attempt is made to remove the holder from the door step, however, the plate 15 will be drawn forwardly over the sill and the flange 16 will contact with the inner side of the door, and thus effectually prevent such removal. The locking plate also prevents the holder from being lifted to such an extent as to permit of the opening of the bottom 9, or the lifting of the holder from the bottle if said holder is open at the bottom.

When the holder is empty the front plate can be swung outward so as to uncover the top of the holder and permit of the introduction of the milk bottle therein, as shown in Fig. 1, but as soon as the bottom of the bottle strikes the top of the cam 12 the lower portion of the front 6 of the holder is thrust outwardly and the upper portion and top 8 are thrust inwardly so that by the time the bottle reaches the bottom of the holder, as shown in Fig. 2, the top will be fully closed, the bottle occupying a position between the back 4 of the holder and the inner face of the cam 12 so as to prevent any swinging movement of the front 6 which would uncover the top of the holder and permit access to the bottle. When the door 3 has been opened and the holder taken indoors the bottom 9 can be readily released and the bottle withdrawn from the holder, as shown in Fig. 3.

I am aware that prior to my invention milk bottle holders have been devised in which the bottle on being introduced into the holder acts upon a cam on the swinging front

plate of said holder and moves said plate, and a top plate carried thereby, to locking position and I am also aware that a bottle holder on the step has been connected to an 5 anchoring device inside the door by a connection passing between the door and door sill. My invention, therefore, so far as the bottle holder is concerned, relies for its novelty upon the simplicity and cheapness of 10 construction of said holder, and the anchoring device relies for its novelty upon the security which it affords as compared with the devices previously employed for this purpose.

15 I claim:

1. The combination of a door and door frame, with a milk bottle holder having a body with pivoted front carrying the top of the holder and having an internally projecting cam which, by engagement with an inserted bottle, locks said front and top members in closed position, said holder also 20

having a drop bottom, and means permanently connected to the body of the holder and under control of the door whereby when 25 the door is closed said bottle holder is anchored vertically in position upon the door step.

2. The combination of a milk bottle holder having a drop bottom with an inflexible anchor plate connected thereto and constructed to bridge the door sill and to position between the same and the bottom of the closed door, said anchor plate having at its inner end a projecting flange which permits the 30 door to swing over it but prevents withdrawal of the plate when the door is closed.

In testimony whereof, I have signed my name to this specification, in the presence of two subscribing witnesses.

PETER A. GOOD.
